UNITED STATES PATENT OFFICE.

DANIEL W. GAGE, OF CAMBRIDGE, MASSACHUSETTS, ASSIGNOR TO J. C. HAWKINS, OF NEWTON, IOWA.

PAPER-FASTENER.

1,130,590.

Specification of Letters Patent. Patented Mar. 2, 1915.

Application filed September 16, 1911. Serial No. 649,622.

To all whom it may concern:

Be it known that I, DANIEL W. GAGE, of Cambridge, in the county of Middlesex and State of Massachusetts, have invented certain new and useful Improvements in Paper-Fasteners, of which the following is a specification.

The present invention relates to a paper fastener of the type in which a tongue is cut in two or more overlapping sheets and is drawn through a slit in the paper by means of a slitting knife having an eye, into which the tongue of paper is placed. The general principle of such a paper fastening machine or implement is disclosed in my application for Patent Sr. No. 560,611, filed May 11, 1910, and I do not therefore claim the principle herein.

The particular object of the invention which is here claimed is to provide a novel and improved tucker for bending over the tongue and placing it in the eye of the slitting knife.

The purpose of the improvement constituting this invention is to make the tucker more positive in its action, stronger and therefore less liable to breakage than hitherto, and more economical in construction.

In the accompanying drawing I have illustrated a form of paper fastening implement or machine in which my invention may be embodied, it being understood that this is merely one of many forms of the machine capable of employing the invention.

Figure 1 represents a side elevation of the entire implement. Figs. 2, 3 and 4 are longitudinal sectional views of the operative parts of the implement showing different steps in the production of a locking tongue. Fig. 5 is a sectional plan view on line 5—5 of Fig. 1. Fig. 6 represents side and edge views of the improved tucker.

The same reference characters indicate the same parts in all the figures.

In the drawings, 1 and 2 represent a pair of jaws movable together and apart by plier handles 3 and 4. One of the jaws as 1, carries a tongue-cutting knife 5, having a U-shaped cutting edge and placed so that the bend of the U is turned toward the outer end of the jaw and the sides thereof are directed away from such end, a slitting knife 6, more distant from the end of the jaw

than said tongue cutter, and a tucker 7. The other jaw carries a platen 8 and a spring plate or gripper 9. The sheets to be united by an integral tongue are shown at 10, and prior to being operated upon are inserted in the space between the platen 8 and the gripper 9. The latter is preferably of stiff strong metal attached to the jaw 2 in such a way that its own resilience urges it toward the platen. It also serves to strip the sheets from the cutter and slitter, and in so doing is prevented from being pulled too far away from the platen 8, by a stop 11 formed on a pin or stud 12 carried by the jaw 2. Said stud also constitutes a gage 70 limiting the extent of possible insertion of the sheets. When the jaws are separated, shoulders 13 on the plier handle 3 engage overlying tongues 14 on the spring plate 9 to hold the same separated from the platen 75 in the position shown in Fig. 1.

The plate 9 has an opening 15 (see Fig. 5) cut in it sufficiently large to admit the tongue cutter 5 freely. At the base of this opening the metal tongue 16 left by the cut 80 is turned up to form a cam having a purpose presently described. The platen 8 also has an opening of sufficient longitudinal extent to receive the tongue cutter and the slitter, and to permit the tongue of paper 85 which is bent back to form the fastening to be withdrawn. The outline of the forward end of this opening is similar to the outline of the tongue cutter, and its edges fit closely around the tongue cutter so as to 90 form the complementary member of a shear or punching device. The cutter 5 constitutes the punch member of this couple and the forward edge of the opening constitutes the die member. 95

The tucker 7 is pivoted on a pin 17 in the interior of the jaw 1 and is contained partially within the space inclosed by the tongue cutter with its face end extending toward the plane of the cutting edge thereof. It projects through a slot 18 in the bow or bend of the cutter, and has a cam surface 19 on the part which thus projects. 100

When the jaws of the machine are advanced toward one another upon a sheet or sheets 10 interposed between them, the spring plate or gripper 9 first bears upon the sheets. Then the tongue cutter 5 and slitter 6 pass through the sheets about at the same time, forming respectively a 110

tongue and a slit. The tucker 7 of which the end is near the end of the tongue cutter, as shown in Fig. 2, bends up the tongue 20 formed by the cutter at about right angles to the sheets. Upon further movement of the jaws together, the surface 19 of the tucker engages the edge 21 of the opening 15 in the gripper 9. This edge constitutes a stop or complementary cam for the cam surface 19. The latter, owing to the resistance and the location of the edge 21, which is at the side of the tucker more remote from the slitter and close to the outer side or bend of the cutter when the latter enters the opening 15, causes the tucker to swing inward toward the slitter, as shown in Fig. 3, placing the end of the paper tongue 20 in the eye 22 of the slitter 6. When the jaws separate, the slitter 20 draws the paper tongue back through the slit in the sheets, making a fastening substantially the same as that illustrated in my application above mentioned. The tucker holds the paper tongue in the eye until such tongue is engaged properly with the slitter. Afterward the tucker is withdrawn by its engagement with the base 23 of the metal tongue 16, which returns the tucker to normal position. This metal tongue serves as 30 a guard to retain the tucker in its proper position, causing it first to bear upon the tongue cut in the paper, near the base of such tongue, and bend up the tongue while the jaws are approaching one another, as shown in Fig. 2, before it is swung back by the cam abutment 21.

The improved tucker above described may be made as a stamping from sheet metal, and thus be inexpensively produced. At the 40 same time it is sufficiently strong to withstand any usage to which it is ever likely to be put, without breaking or bending, and is moreover positively actuated by the abutment face or edge 21, so that it cannot fail to bring the paper tongue into the position shown in Fig. 3 in the eye of the slitter, however much the resistance of the paper tongue may be.

It will be readily understood that my invention is applicable to an implement or machine of any character whatever which is provided with a tongue cutter and a slitter having an eye, whether the same are carried by the jaws of a hand implement such as 55 that shown, or by any other moving parts.

I claim,—

1. The combination in a paper fastening machine having a tongue cutter and a penetrating device or slitter, of a tongue folder or tucker pivotally mounted within the tongue cutter, and means for positively swinging the tucker from the tongue cutter toward the slitter after said parts have penetrated the paper.

2. The combination in a paper fastening

machine having a tongue cutter and a penetrating device or slitter, of a tongue folder or tucker pivotally mounted within the tongue cutter, and a stripper plate having a part to coact with the tongue folder to positively swing it toward the penetrating device.

3. In a paper fastening apparatus having relatively movable members, one of which carries a die and the other a tongue cutter and a penetrating device for forming an opening through which the tongue is passed to fasten the paper, a tongue tucker pivoted within and normally lying within the cutter, and means supported by the die carrying member for positively moving the tucker out from within the cutter after the cutter has penetrated the paper.

4. The combination in a paper-fastening machine having a tongue cutter and a slitter, provided with an eye, of a tucker pivotally mounted within the tongue cutter, and cam means for positively swinging the tucker toward the eye of the slitter.

5. In a paper-fastening machine, the combination of relatively movable opposed members, a tongue cutter on one of said members, a slitter having an eye on one of said members, said cutter and slitter being adapted to penetrate sheets placed between the members when the members are moved relatively together, a tucker pivoted upon one of the members and having a cam surface, and an abutment on the other member arranged to engage such cam surface when the members are brought together and 95 forcibly move the tucker about its pivot.

6. In a paper-fastening machine, the combination of relatively movable opposed members, a tongue cutter on one of said members, a slitter having an eye on one of said members, said cutter and slitter being adapted to penetrate sheets placed between the members when the members are moved relatively together, a tucker pivoted upon one of the members and having a cam surface, and an abutment on the other member arranged to engage such cam surface when the members are brought together and 105 forcibly move the tucker about its pivot, said cam surface and abutment being on the side of the tucker 110 more remote from the slitter, whereby the tongue cut in the sheets is forcibly placed in the slitter eye.

7. In a machine of the character described, the combination with a tongue cutter, a slitter, a tucker contained within the tongue cutter, and having a cam portion projecting beyond the tongue cutter on the side opposite from the slitter, and an opposed abutment arranged with provision for relative movement toward and from the tucker, and adapted to engage the cam portion of the same and force it toward the slitter.

8. A paper fastening machine comprising a tongue cutter, a slitter having an eye, a

5 tucker pivotally mounted with its free end in the space bounded by the tongue cutter, a cam arranged to project said tucker toward the eye of the slitter when the latter is in the paper, and a cam for returning the tucker to its former position after withdrawal from the paper.

10 9. A paper-fastening machine comprising a pair of members movable relatively together and apart; a tongue cutter having a U-shaped cutting edge, a slitter having an eye, and a tucker, all carried by one of said members, and cams or abutments carried by the other member and so arranged that the tucker may pass between them when the members move together, one of said cams or abutments being arranged to project the tucker toward the slitter eye on the movement of the members together, and the other to withdraw it on the movement apart.

15 10. A paper-fastening machine comprising a pair of jaws and means for moving said jaws relatively toward and from one another, a tongue cutter carried by one of the jaws, and projecting toward the other, having a cutting edge on its end in the form of the letter U, the bend of the U being toward the end of the jaw and the sides thereof directed away from such end, a slitter secured to one of the jaws at a greater distance from the end of the jaw than the cutter, a tucker pivoted to one of the jaws and extending toward the other with its free end contained in the space inclosed by the cutting edges of the cutter, the intermediate part of the tucker being formed as a cam and located between the cutter and the end of the jaw, a cam abutment carried by the other jaw arranged to pass close to the outer side of the cutter when the jaws move together, and to bear on the cam surface of the tucker and force the end of the latter toward the slitter, and a second cam abutment on the jaw opposite to that which carries the tucker arranged on the opposite side of the tucker and cutter from the first named cam abutment, and arranged to return the tucker to its first position when the jaws move apart.

20 11. In a paper-fastening machine, a tongue cutter, a slitter provided with an eye, a tucker independent of both the cutter and slitter movably mounted, and positive means for so moving the tucker as to place a tongue formed by the cutter in the eye of the slitter.

25 12. In a paper - fastening machine, a tongue cutter, a slitter provided with an eye, a tucker independent of both the cutter and slitter, pivotally mounted to swing between the cutter and slitter, and means for positively forcing the swinging end of the tucker toward the slitter to tuck a tongue of paper formed by the cutter, into the eye of the slitter.

30 13. In a paper-fastener, the combination

of a cutting knife shaped and located to form a tongue from the paper, and having an aperture back from that portion of its edge which forms the tip of the tongue, a slitting knife to slit the paper near the base 70 of the tongue, said slitting knife being provided with an eye near its slitting edge, a tucker separate from said slitting knife for causing the latter to draw the end of the tongue through the slit in the paper, and 75 having a cam portion extending through said aperture in the cutting knife, and a complemental cam abutment arranged to engage said cam portion and force the tucker toward the slitting knife when the knives 80 are passed through the paper.

14. In a paper fastener, the combination of a cutting knife to form a tongue from the paper, a slitting knife to slit the paper near the base of said tongue, said slitting knife 85 being provided with an eye near its slitting edge, a folder separate from said cutting knife and slitting knife and normally having its free end away from the eye of the slitting knife, and means for positively actuating said folder to bend said tongue through said eye, whereby the slitting knife automatically draws the end of the tongue 90 through the slit when said knife is withdrawn.

95 15. In a paper-fastener, the combination of a cutting knife to form a tongue from the paper, a slitting knife to slit the paper near the base of said tongue, said slitting knife being provided with an eye near its slitting 100 edge, a folder separate from said cutting knife and slitting knife and normally having its free end away from the eye of the slitting knife, and means for shifting said folder toward said slitting knife to cause 105 the free end of said folder to bend the tongue through said eye, whereby the slitting knife automatically draws the end of said tongue through the slit when the knife is withdrawn.

110 16. In a paper-fastener, the combination of a pair of jaws, a cutting knife to form a tongue from the paper, a slitting knife to slit the paper near the base of the tongue, said knives being rigidly mounted in one of 115 said jaws, a folder associated with said knives for causing the slitting knife to draw the end of the tongue through the slit in the paper when the jaws are opened, said folder being separate from said slitting 120 knife, means for closing and opening said jaws, and means for positively moving the folder toward the slitting knife when the jaws are closed.

125 17. In a paper-fastener, the combination of a cutting knife to form a tongue from the paper, a slitting knife to slit the paper near the base of the tongue, said slitting knife being provided with an eye near its slitting edge, a folder separate from said 130

cutting knife and slitting knife for causing the latter to draw the end of the tongue through the slit in the paper, and means for forcing said folder into folding position.

5 18. In a paper fastening machine having a tongue cutter and a slitter provided with an eye, a movably mounted tucker independent of the cutter and slitter adapted to place the end of a tongue formed by such cutter in the eye of the slitter, and having its greatest strength and stiffness in the plane in which force is applied to and by it.

15 19. In an implement for securing together a plurality of sheets, the combination of a die-plate, a cutting member movable into said die-plate to cut a tongue from the paper, a slitting knife movable through said die-plate to slit the paper near the base of the cut tongue and having an eye for receiving the ends of said tongue, a stripper plate, and a folder independent of and pivoted between said knives and mounted to swing under said stripper plate when folding the paper tongue into the eye of the slitting knife, said stripper plate having means for causing said folder thus to swing.

30 20. In a paper fastener, the combination of a cutting knife adapted to form a tongue from the paper, a slitting knife arranged to slit the paper near the base of the tongue, said slitting knife being provided with an eye, a folder separate from said cutting knife and slitting knife and pivotally mounted to fold the paper tongue backward 35 toward said eye, and means for swinging said folder on its pivot to fold the paper tongue backward through the eye of the slitting knife.

40 21. A paper fastening implement comprising pivotally connected arms having handle portions by which they may be moved together, a punch carried by one of said arms, a die carried by the other arm, said punch and die having coöperating U 45 shaped shearing edges, whereby to form a tongue in the material operated upon and leave such tongue attached at one edge to the material, an inclined tongue bender carried by one of said arms and contained within said punch, arranged to strike a portion 50 of the other arm and to be thereby swung toward the paper to lay the tongue back against the same, and a piercing device 55 projecting from one arm beside the open side of the punch, and having an eye into which the end of the tongue is passed by said tongue bender.

60 22. In combination in a paper fastening device of the type described, a carrier, a punch having side walls, a needle, said punch and needle being mounted on the carrier, and a tucker pivotally mounted between the side walls of the punch.

65 23. In an implement for securing together a plurality of paper sheets, the combination

of a die plate, a cutting member movable with a straight line motion into said die plate to cut a tongue from the paper, a slitting knife movable through said die plate to slit the paper near the base of the cut tongue and having an eye for receiving the end of said tongue, a stripper plate, and a rigid folder independent of said cutting member and slitting knife and pivoted therebetween, said folder being mounted to swing under said stripper plate when folding the paper tongue into the eye of the slitting knife, and means for camming said rigid folder to swing it under said stripper plate.

70 24. In a paper fastener, the combination of a cutting knife shaped to form a tongue from the paper, a slitting knife adjacent to said cutting knife and adapted to slit the paper near the base of the tongue, said slitting knife being provided with an eye near its slitting edge, a substantially rigid folder separate from said cutting and slitting knives, a pivot whereon said folder is pivotally mounted between said knives, said folder being movable toward the eye of the slitting knife to fold the paper tongue backward, and camming means which comes into striking engagement with said folder near the end of the downward movement of said cutting and slitting knives to insure positive action of said folder on the paper tongue when said folder is near the limit of its folding movement.

75 25. In a paper fastener, the combination of a cutting knife adapted to form a tongue from the paper, a slitting knife arranged to slit the paper near the base of the tongue, said slitting knife being provided with an eye, a folder separate from said knives and 80 pivotally mounted to fold the paper tongue backward toward said eye, and a stripping plate having a part for swinging said folder on its pivot to fold the paper tongue backward through the eye of the slitting knife.

85 26. In a paper fastener, the combination of a cutting knife to form a tongue from the paper, a slitting knife for slitting the paper near the base of the tongue, said slitting knife being provided with an eye near 90 its cutting edge, a folder separate from said knives and arranged to push the tongue of paper backward through the eye of said slitting knife, a stripper mounted to hold the sheets of paper during the cutting operation, said stripper having a part which comes into contact with said folder to complete the folding operation.

95 27. In a device for securing together a plurality of sheets of paper, the combination of a pair of jaws movable one toward another, a die plate carried by one of said jaws, a cutting knife carried by the other jaw, a slitting knife movable with said cutting knife, a stripper plate for disengaging 100

the paper sheets from the knives after the cutting operation, and a folder pivoted to said upper jaw and arranged for folding the cut paper backward toward the slitting 5 knife, said folder having a part arranged for contact with a portion of said stripper to complete the folding movement.

In testimony whereof I have affixed my signature, in presence of two witnesses.
